US00D359479S

United States Patent [19]

Jondrow et al.

[11] Patent Number: Des. 359,479

[45] Date of Patent: ** Jun. 20, 1995

[54] COMPUTER INPUT DEVICE

[75] Inventors: Timothy J. Jondrow; Michael D. Derocher, both of Corvallis, Oreg.
 [73] Assignee: Hewlett-Packard Corporation, Palo Alto, Calif.
 [**] Term: 14 Years
 [21] Appl. No.: 3,560
 [22] Filed: Jan. 12, 1993

Related U.S. Application Data

[63] Continuation-in-part of Ser. No. 856,436, Mar. 23, 1992.

[57] CLAIM

The ornamental design for a computer input device, as shown and described.

DESCRIPTION

FIG. 1 is a top perspective view of a computer input device showing our new design;
FIG. 2 is a perspective view of the computer input device slightly enlarged as compared to FIG. 1;
FIG. 3 is a left-side elevational view of the computer input device;
FIG. 4 is a right-side elevational view of the computer input device;
FIG. 5 is a top plan view of the computer input device;
FIG. 6 is a bottom plan view of the computer input device;
FIG. 7 is a rear elevational view of the computer input device;

FIG. 8 is a front elevational view of the computer input device;
FIG. 9 is a top perspective view of the computer input device shown in expanded position;
FIG. 10 is a front elevational view of the computer input device;
FIG. 11 is a rear elevational view of the computer input device;
FIG. 12 is a top plan view of the device;
FIG. 13 is a bottom plan view of the computer input device;
FIG. 14 is a left-side elevational view of the computer input device; and,
FIG. 15 is a right-side elevational view of the computer input device.
The extension arm in FIGS. 2, 6-13 is partially shown for ease of illustration. The computer input device is shown in an expanded position in FIGS. 10-15.

FIG. 5

FIG. 6

FIG. 7

FIG. 8

FIG. 9

FIG. 10

FIG. 11

FIG. 14

FIG. 15
